STORM SASH OPENER

Filed May 16, 1925

Inventor
John N. Peaslee

John N. Peaslee

Attorney

UNITED STATES PATENT OFFICE.

JOHN N. PEASLEE, OF ST. PAUL, MINNESOTA.

STORM-SASH OPENER.

Application filed May 16, 1925. Serial No. 30,849.

My invention relates to storm sash openers and holders, wherein it is designed to provide a very practical holding means for the storm sash so that it cannot rattle when it is held in open position or so that it can be adjusted to any degree of opening to hold the storm sash rigid at the free end of the same.

A feature of my invention resides in a fastener and holder for the storm sash which is provided with a rod having a head formed thereon which extends through the sash, with the inner end of the rod secured to the casing to prevent the sash from flying back and forth on the rod. The shoulder on the end forming the limit of movement of the free end of the storm sash or screen which this holder may be secured to, to limit the outer swinging movement of the free end of the same.

It is also a feature of my invention to provide means which is securely attached to the storm sash or frame through which the rod extends and which is provided with a screw clamp so that it can readily engage the rod to clamp the same on the rod and hold the sash in set position. The set screw of the clamp engages the surface of the rod to bite into the same to hold the sash rigid in relation to the rod. The clamping member is secured firmly to the storm sash and held rigidly therewith, while the rod is attached pivotally to the casing and extends through the sash, preferably through an opening formed centrally between the sides of the same, with the stop shoulder or head on the outer end, outside of the sash frame, so as to form a stop to limit the outward swing of the sash. This construction provides a holding means for holding the sash firmly at the center of the same, so that it cannot vibrate and make a noise as is often apparent with various holders. The fact that it only requires one holder at the center, which holds the window very firmly in place makes it more economical for use than where side holding members are required.

These features, together with other important details of construction will be more fully set forth in the specification and claims. It is to be noted however that the extreme simplicity of my holder is of im-

portance in carrying out my invention and it is important in providing a holder which permits the window to be adjusted in any degree of opening. This is not ordinarily found in storm sash and screen holders, thus my holder can be adjusted so as to hold the screen or the window open to the desired degree, and yet hold it rigid and firm so that the wind cannot possibly blow it loose, under ordinary conditions.

In the drawings forming part of this specification:

Figure 1 illustrates a side view, partly in cross section of a window casing, illustrating my opener for storm sashes in use.

Figure 2 illustrates a side view, partially in cross section in enlarged detail of my storm sash opener removed from the window casing.

Figure 3 is a plan view of the portion of the window casing in enlarged detail illustrating the rod removed from the storm sash and held by the grip on the sash frame when not in use as a holder for the storm window.

Figure 4 is a section on the line 4—4 of Figure 2.

Figure 5 is a plan view of the clip cap for holding the one end of the rod of my storm sash opener and holder.

Figure 6 is a front elevation of the clip illustrated in Figure 5, on the line 6—6.

In the drawings, my storm sash opener and holder A is formed with a rod 10, having a head 11 formed on one end thereof and an eye-opening 12 formed on the other end.

The rod 10 of my holder and opener A is of a simple formation and the head 11 forms a shoulder or stop to engage against the outside of the storm sash B to limit the outer movement of the same, as illustrated in Figure 1, while the inner end formed with the eye 12 engaged by the screw 13 under the clip cap 14.

The cap 14 protects the inner eye end 12 of the rod 10 and permits free movement of the inner end of the rod 10 beneath the cap 14, so that it is provided with the necessary pivotal movement to operate freely in the opening and closing of the storm sash. The clip cap 14 held by the screw 13 to the bottom of the window sash 15 as illustrated in the drawing in Figure 1. The cap 14 is

practically of a quarter spherical shape and is provided with an open end 16, through which the rod 10 extends.

The rod 10 adapted to extend through the bottom or free end of the storm sash C so that the free end of the storm sash will slide freely along the surface or body of the rod 10, between the eye 12 and the shoulder head 11. This permits the sash B to be opened the limitation of the length of the rod 10.

When the rod 10 is not desired for use to hold the storm sash it may be disengaged from the sash B and held in the position illustrated in Figure 3, with the clip 14 firmly fixed over the end of the rod or the eye 12, and the clip turned about so that the end 16 extends away from the rod 10 while the rod 10 is engaged by the notch 17 formed in the clip cap 14 which is adapted to fit over the same and hold the rod 10 extending longitudinally along the sash base 15. This opening 17 is practically semi-circular or of the shape of the cross section of the rod 10, so as to fit over the same, and thus the clip cap 14 is adapted to hold the rod firmly on the window sash 15, in the summer when it is not desired for use for the storm sash frame B. It is obvious, however, that my holder can be used to hold screens if it is so desired. This would permit them to be opened at the bottom when it is desired, if they are hung on the ordinary well-known hinges or hinging connections at the top. In the drawings I have not illustrated the top of the storm sash B as hung to the window frame C, as this is of ordinary well-known construction. The window frame B is broken off short of the hinging connection.

I provide a clamping member E in my storm sash opener and holder which is made up of a member formed of flat material bent so that it is provided with a flat cleat end 18, through which the screw openings 19 extend. The openings 19 are adapted to receive screws which hold the plate 18 against the inner surface of the free end of the sash B.

The clamp member E is bent to extend at approximately right angles from the plate portion 18 to form the horizontal portion 20, and is then bent again at right angles to form the portion 21 and from this portion 21 it is bent at right angles back toward the plate 18 to form the portion 22, which extends practically parallel to the portion 20. An elongated opening 23 is formed in the portion 21 which is adapted to receive the eye 12 through the same and permits the rod 10 to be clamped and engaged by the set screw 24 which is threaded through the portion 20 and bites into the rod 10 to clamp the same against the lower surface 22 of the clamp E, as illustrated in Figure 2. The set

screw can be easily set to engage the rod 10 and thus hold the storm sash B in any position or degree of opening on the rod 10.

When the plate 18 is firmly secured to the sash B and is extending over the rod 10 the set screw 24 can be engaged and firmly made to bite the rod 10. This will hold the storm sash or frame B in any desired position within the limits of the length of the rod 10.

Only one of the storm sash openers and holders A is required to hold the ordinary window frame and this can be placed centrally between the sides of the same at the free end, with the rod 10 extending through the frame, and thus the rod is adapted to firmly and rigidly support the free end of the frame B. I have found in actual, practical use that my holder holds the window against rattling and so firmly that it formed a most desirable storm sash opener and holder. It is particularly desirable because it holds the window against opening wide, and thus prevents any one crawling through the window or opening it wide enough so as to disturb the occupants of the home.

The portion 22 of the clamp E is recessed or grooved at 25 to receive the shape of the rod 10 and when the set screw 24 is set tightly against the rod the rod will lie in the recess or groove 25 along the portion 22. This forms a very rigid holding means for the rod.

The simplicity of my device is quite apparent and it will be clearly noted that it is quite desirable as a holding means for storm sash or window screen frames, to hold the free end so that it can be opened or held firmly closed. Therefore my storm sash holder and opener is very desirable for this means and where it is desired to hold the window firmly against rattling.

In accordance with the patent statutes I have described the principles of operation of my storm sash opener and holder, and I desire to have it understood that the drawings are only illustrative of a particular formation of the same, the invention can be carried out by other means and applied to uses other than those above set forth within the scope of the following claims.

I claim:

1. A storm sash holder including a rod, a plate secured to the storm sash adapted to engage said rod and having a slotted opening therein for said rod and a longitudinally extending groove partially surrounding said rod and a set screw in said plate adapted to force said rod into said groove and clamp it therein.

2. A storm holder including a rod adapted to extend through an opening in the storm sash at the free end thereof, clamping means upon said storm sash for said rod, means for engaging one end of said rod to

hold the same pivotally connected to the window frame including a shell like member of a quarter-spherical shape.

3. A storm sash holder including a rod adapted to extend through an opening in said storm sash at the free end thereof, clamping means upon said storm sash for said rod, means for engaging one end of

said rod to hold the same pivotally connected to the window frame including a shell ¹⁰ like member of a quarter-spherical shape pivotally secured to the said frame and having a notch therein for the reception of the rod.

JOHN N. PEASLEE.
